(57) **CLAIM**

The ornamental design for a cap, as shown and described.

DESCRIPTION

FIG. 1 is a perspective view of the cap, showing our new design in an environment of use;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a perspective view of the cap;
FIG. 9 is a front elevation view thereof;
FIG. 10 is a rear elevation view thereof;
FIG. 11 is a right side elevation view thereof;
FIG. 12 is a left side elevation view thereof;
FIG. 13 is a top plan view thereof; and,
FIG. 14 is a bottom plan view thereof.

In the drawings, the broken lines show portions of a cap and the broken lines in FIGS. 1-7 show portions of an aerosol container that form no part of the claim.

1 Claim, 6 Drawing Sheets
